UNITED STATES PATENT OFFICE.

ERNEST H. PRABODY, OF FELHAM MANOR, NEW YORK, ASSIGNOR TO PRABODY ENGINEERING CORPORATION, OF NEW YORK, N. Y., A CORPORATION OF NEW YORK.

APPARATUS AND METHOD FOR BURNING LIQUID FUEL.

Application filed June 7, 1922. Serial No. 566,569

My invention relates to a method of atomizing liquid fuel mechanically or by means of centrifugal force without the use of steam or other atomizing medium, and to an apparatus for carrying out such a method. More particularly the invention relates to a system whereby the capacity or rate of atomization of the fuel necessary to meet fluctuating demands may be controlled through a wide range by simple means, and whereby a large number of atomizers may all be controlled at one central point which may be at a considerable distance from the atomizers themselves. Furthermore the invention includes means whereby such control may be effected without any decrease in the efficiency of the device.

All mechanical atomizers now in general use having a fixed orifice, while possessing many advantages, have been subject to a very serious limitation as regards range of capacity; that is, burners which were designed for certain maximum rates of operation could not be satisfactorily operated at capacities materially lower than this maximum. This is due to the obvious fact that as the atomizing power of the burners depends on the whirling motion of the liquid in the central chamber of the tip, and as the whirling motion depends on the velocity of the liquid entering tangentially into this chamber, which velocity in turn depends upon the capacity, then any lowering of the capacity lowers the velocity, reduces the whirling motion, and thus lowers the atomizing power and reduces the efficiency of the apparatus.

The method necessarily followed with this type of apparatus when it is necessary to meet fluctuating load conditions requires the attention of a large operating force to change the effective size of the tips or to place burners in or out of service. This involves constant care and attention with resulting expense, and is otherwise unsatisfactory.

This invention has for its objects the production of a method of centralized control which may be employed with any desired number of burners that is simple in arrangement and operation which can be placed in the hands of one intelligent operator, which not only saves labor and wear and tear on the apparatus but results in greatly improved efficiency of operation.

Particularly is this true where the central control station is provided with instruments for observing and recording the draft pressures and other guides to good operating conditions.

Another object of the invention is the production of a simple form of atomizer of extremely wide range of capacity, which shall be of low cost, easily repaired and particularly accessible for cleaning and maintenance.

Another object is to so arrange the parts and particularly the by-pass orifices that a more regular and efficient operation shall be obtained under all varying rates of discharge.

Other objects will be evident from the following detailed description and the appended claims.

In the drawings:

Figure 1 is an end view of the atomizer.

Figure 2 is a side view, partly in section.

Figure 3 is a section through the plug on the line 3—3 of Figure 4.

Figure 4 is an end view of the plug.

Figure 5 is a section through the tip on the line 5—5 of Figure 6.

Figure 6 is an end view of the tip.

Figure 7 is a longitudinal section through the atomizer, showing the tip, plug, and cap assembled in connection with adjacent parts.

Figure 8 is an end view of the atomizer showing the tip with outlet orifice.

Figure 9 is a front view of the atomizer shown in connection with an air register installed on the furnace front and provided with delivery and return pipe connections.

Figure 10 is a longitudinal section through the structure shown in Figure 9.

Figure 11 is a front view of a furnace front fitted with five atomizers and associated air registers, and showing the proper arrangement of delivery and return pipes.

Figure 12 is a section through the furnace on the line 12—12 of Figure 11.

Figure 13 is a diagrammatic plan view of a complete installation including twelve atomizers set in four furnaces together with the proper piping, valves, pumps, heaters, strainers and tank.

Figure 14 is a front elevation of the same general arrangement, diagrammatically illustrated in part.

The atomizer comprises a tip 1 held in

place by a cap 2 which screws on to the burner barrel 3 and is thus held in place against a plug 4 which communicates with an inner tube 5 by means of a stem portion 6 which makes a sliding fit and provides for lateral motion while at the same time it seals the annular space 7 from the space 8 on the inside of the tube 5. A bevelled portion 9 of the cap 2 engages with a similar bevelled portion 10 on the tip 1, and these are both concentric so that the tip is centered and fixed in proper position when the cap is screwed upon the burner barrel 3. An inclined face 11 on the end of the burner barrel 3 is engaged by a similar face 12 on the plug 4, thus centering the latter. In this manner the tip 1 and plug 4 are always held in proper alignment when assembled. Both of these pieces are carefully made with flat seats or faces, which when held together as shown, make an oil tight fit.

The tip 1 has a projecting portion 13 which extends beyond the face of the cap 2 when assembled and facilitates separation of the two parts. That is, if on removal of the cap, the tip and cap adhere together, the projecting portion 13 of the tip can be tapped lightly against a flat surface and at the same time ample protection is provided for the orifice 14, the accuracy and perfect roundness of which is essential for proper atomization. The orifice 14 communicates with a central chamber 15 preferably of a conical shape which in turn communicates with a cylindrical chamber 16. The orifice 14 and two chambers 15 and 16 are therefore in direct communication.

In the face of the tip 1 a channel 17 surrounds the central chamber 16 and communicates therewith by means of accurately machined channels 18 which enter the central chamber tangentially. There may be any desired number of these channels depending on the designer's choice and they may be of any cross section, the square section shown being preferable. The plug 4 is provided with a series of holes or passages 19, which extend through the main portion of the plug, being located just outside of the sleeve 6 and preferably parallel therewith. A series of smaller holes 20 also extend through the main part of the plug, but are placed nearer the center so that they communicate with the space inside of the sleeve.

When the tip and plug are assembled together on the burner barrel and with the sleeve of the plug fitting over the inner tube, it will be observed that the annular space 7 within the burner barrel and exterior to the inner tube, communicates by means of the passages 19 in the plug with the circular channel 17 and this in turn communicates through the slots 18 with the central cham-

ber 16 and the chamber 15. Thus there are provided two outlets from this chamber, one through the orifice 14 and one through the small holes 20 into the space 8 which is separated from the space 7 by the walls 70 of the inner tube and the sleeve of the plug.

The passages 18 leading into the central chamber are so arranged as to be substantially tangential to the walls of the chamber 16. The holes 20 are arranged adjacent to the periphery of the chamber.

The burner barrel at its rear end is screwed into a fitting 21 which has a projection 22 provided with a recess which engages with a projection of the fitting 23, the two together forming a coupling or union and being held in place by means of the yoke 24, which is pivoted at 24' and held in operative position in any suitable manner, thus providing means by which the parts of the coupling may be quickly released.

The fitting 23 is provided with suitable passages (not illustrated) which communicates with pipes 25 and 26 and lead into corresponding passages into the fitting 21. By means of a central diaphragm or partition the fitting 21 is divided into two chambers. The inner tube 5 screws into this partition and communicates with an opening leading into the rear chamber, while the burner barrel screws into the fitting and is in communication with the forward compartment. This entire arrangement, with additional details is shown and claimed in my companion application Serial No. 543,841, filed March 15, 1922.

When the atomizer is entirely assembled and coupled up as shown in Figures 1 and 2, the various passages coordinate so that there is direct communication from the inlet pipe 25 through the passages in fittings 23 and 21 to the forward compartment in fitting 21 and thence to the annular space between the inner tube and the inner wall of the burner barrel, and thus to the space 7, through the passages 19 to the channel 17, through the tangential passages 18 to the central chamber 16, thence through the chamber 15 and orifice 14, or back through the small openings 20 into the space 8, through the inner tube 5 to the rear compartment in the fitting 21, and so on through the coupling and fitting 23 to the outlet pipe 26.

The fitting 23 is attached to a pipe 27 which surrounds the burner barrel when the apparatus is assembled, and which in turn is supported in the hub 28 of the front plate 29 of the air register. The latter is provided with air doors 30 which may be adjusted and locked in any desired position by the control mechanism 31.

The inlet and outlet pipes 25 and 26 communicate through flexible connections 130

with the supply and return pipes and are provided at 34 and 35 with valves for shutting off the flow of oil when the burner is to be uncoupled and removed for cleaning. The valve 35 is a combined stop and check valve, the check preventing the return of oil from the discharge line, so that in taking out a burner for cleaning it is merely necessary to close valve 34. The valves 36 and 10 37 are merely for additional protection.

When connected in multiple on a furnace, additional valves 38 and 39 are provided on the delivery and return pipes 32 and 33. Also it is advisable to provide a valve 40 15 connecting the delivery and return systems together if desired, as for example to permit the circulation of oil when warming up.

Figures 13 and 14 indicate the method of connecting up a large number of burners in 20 a multiple number of furnaces. The liquid is stored in a tank 44 and is drawn by means of a pump 46 through a suction strainer 45 and forced under pressure through the heaters 47 and through delivery strainers 48 into 25 the delivery line 32 which leads by various branches to the various furnaces and delivers the oil to the inlet side of the burners as shown in Figure 11.

The return pipes lead back from the individual burners preferably parallelling the 30 delivery lines and control valves are provided on the branches from each furnace as at 39 and from each group of furnaces as at 41, and from the entire system as at 42. 35 Valves 43 and 49 are also provided to make it optional as to whether the returned oil is delivered back to the tank through the valve 43 or to the suction of the pump through the valve 49. It is obvious that 40 according to which plan is followed, valves 43 or 49 may be used for controlling the entire system in place of valve 42.

The operation will be apparent from the 45 above description, but may be briefly stated as follows. When the return of the oil through pipe 26, Figure 1, is prevented, either by closing valve 35 or 37 of any individual burner, or by closing valve 39, affecting all the burners of one furnace, or 50 by valve 41, affecting all the burners of a group of furnaces, or by valve 42 affecting all of the burners that are operating, all of the burners that are affected will act as straight mechanical atomizers at maximum 55 capacity. The oil will enter each burner through the connection 25, and so on as previously described to the space 7, through holes 19, the tangential passages 18 and to the central chamber 15 where it acquires a 60 rapid whirling motion. It then passes out through the orifice 14 in the tip and into the furnace in the form of a spray. No oil will be allowed to flow back through the small openings 20, and all of the oil which enters

the central chamber will leave the tip as sprayed fuel.

If, however, the return valve on any burner or group of burners is opened or partially opened, some of the oil which enters the central chamber will flow back 70 through the plug and inner tube 5 and so on to the return lines, while the oil which will be delivered to the furnace in a spray will vary in amount according to the proportion of oil which is allowed to return or 75 "by-pass," that is, according to the amount of opening of the return valve. At the same time it is obvious that the total amount of oil flowing through the system remains undiminished and as all of this oil enters the 80 central chamber of the various burners, it is evident that the velocity through the tangential slots is fully maintained, and therefore that there is no reduction in atomizing power. 85

The use of strainers in the system is for the purpose of removing any extraneous matter which might clog the tips or other passages. The heaters are employed for the 90 purpose of reducing the viscosity of the oil to the necessary degree for spraying.

I am aware that certain attempts have been made to provide flexibility for the mechanical atomizers, and that central spindles have been employed by means of which the capacity of a single burner may be controlled but I do not know of any method whereby the control of the flow of the fuel to and from a plurality of atomizers connected in parallel in a single supply and single discharge line with a portion of the fuel bypassing the orifice through the center of the atomizers, is used; and, it is upon this important advanced step in the art I base my 100 claims for it is readily understood that while individual adjustment of atomizers may give satisfactory results in installations in which only one burner is used it becomes impractical in large plants where many burners are used for the reason that individual burner control requires the same labor and attention that the earlier types require, since it is just as easy to put out and light up a burner individually as by adjustment of a 105 spindle. 110

It is obvious that many changes may be made in the details shown without departing from the spirit of my invention. So far as the general system and method of regulation is concerned it is not necessary to use the precise form of atomizer here shown. In general it is to be understood that the invention is limited only by the scope of the appended claims. 115

I claim:

1. A method for controlling the combustion of liquid fuel which comprises delivering the fuel to a plurality of points of atom-

- ization arranged in groups, imparting a whirling motion to said fuel prior to atomization, returning a portion of said fuel after imparting the whirling motion thereto, and regulating the return of fuel from all of said points collectively.
2. A method for controlling the combustion of liquid fuel which comprises delivering the fuel to a plurality of points of atomization arranged in groups, imparting a whirling motion to said fuel prior to atomization, returning a portion of said fuel after imparting the whirling motion thereto, and regulating the return of fuel from all of said points individually and collectively.
3. A method for controlling the combustion of liquid fuel which comprises delivering the fuel to a plurality of points of atomization arranged in groups, imparting a whirling motion to said fuel prior to atomization arranged in groups, imparting a whirling motion to said fuel prior to atomization after imparting the whirling motion thereto, and regulating the return of fuel from all of said points individually, by groups, and collectively.
4. A method for controlling the combustion of liquid fuel which comprises delivering the fuel to a plurality of points of atomization arranged in groups, imparting a whirling motion to said fuel prior to atomization and simultaneously regulating the amount of atomized fuel discharge at said points while maintaining substantially uniform the pressure of fuel supplied to each point of atomization.
5. A method for controlling the combustion of liquid fuel which comprises delivering the fuel to a plurality of points of atomization arranged in groups, imparting a whirling motion to said fuel prior to atomization, regulating the discharge of fuel at each point individually while maintaining substantially uniform the pressure of fuel supplied to each point of atomization, and regulating the discharge of fuel at all points collectively.
6. In an apparatus for burning liquid fuel, in combination, a fuel supply line, a return line, a plurality of mechanical atomizers connected in parallel between the lines, means for controlling the return of the fuel through a single return passage.
7. In an apparatus for burning liquid fuel, in combination, a fuel supply line, means for supplying fuel under pressure to said line, a return line, a plurality of mechanical atomizers connected in parallel between the lines, means for regulating the return of part of the fuel through a single passage through the center of each of the atomizers.
8. In an apparatus for burning liquid fuel, in combination, a nozzle comprising a tip provided with an orifice and tangential passages all self contained, an abutment plug provided with a plurality of straight parallel holes and adapted to abut against the aforesaid tip, means for supplying a maximum amount of fuel under pressure to the tangential passages, means for returning a part of the fuel through the abutment plug and means for controlling the amount of fuel thus returned.
9. An apparatus for burning liquid fuel comprising a plurality of atomizers, a fuel return pipe from each atomizer, a fuel return pipe common to a group of burners, and means for separately controlling the flow of fuel through each of said return pipes.
10. An apparatus for burning liquid fuel comprising a plurality of atomizers, a fuel return pipe from each atomizer, a fuel return pipe common to a group of burners, a fuel return pipe common to a plurality of groups of burners, and means for separately controlling the flow of fuel through each of said return pipes.

In testimony whereof I affix my signature.
ERNEST H. PEABODY.

- ization arranged in groups, imparting a whirling motion to said fuel prior to atomization, returning a portion of said fuel after imparting the whirling motion thereto, and regulating the return of fuel from all of said points collectively. 5
2. A method for controlling the combustion of liquid fuel which comprises delivering the fuel to a plurality of points of atomization arranged in groups, imparting a whirling motion to said fuel prior to atomization, returning a portion of said fuel after imparting the whirling motion thereto, and regulating the return of fuel from all of said points individually and collectively. 10
3. A method for controlling the combustion of liquid fuel which comprises delivering the fuel to a plurality of points of atomization arranged in groups, imparting a whirling motion to said fuel prior to atomization arranged in groups, imparting a whirling motion to said fuel prior to atomization after imparting the whirling motion thereto, and regulating the return of fuel from all of said points individually, by groups, and collectively. 15
4. A method for controlling the combustion of liquid fuel which comprises delivering the fuel to a plurality of points of atomization arranged in groups, imparting a whirling motion to said fuel prior to atomization and simultaneously regulating the amount of atomized fuel discharge at said points while maintaining substantially uniform the pressure of fuel supplied to each point of atomization. 20
5. A method for controlling the combustion of liquid fuel which comprises delivering the fuel to a plurality of points of atomization arranged in groups, imparting a whirling motion to said fuel prior to atomization, regulating the discharge of fuel at each point individually while maintaining substantially uniform the pressure of fuel supplied to each point of atomization, and 25
6. In an apparatus for burning liquid fuel, in combination, a fuel supply line, a return line, a plurality of mechanical atomizers connected in parallel between the lines, means for controlling the return of the fuel through a single return passage. 30
7. In an apparatus for burning liquid fuel, in combination, a fuel supply line, means for supplying fuel under pressure to said line, a return line, a plurality of mechanical atomizers connected in parallel between the lines, means for regulating the return of part of the fuel through a single passage through the center of each of the atomizers. 35
8. In an apparatus for burning liquid fuel, in combination, a nozzle comprising a tip provided with an orifice and tangential passages all self contained, an abutment plug provided with a plurality of straight parallel holes and adapted to abut against the aforesaid tip, means for supplying a maximum amount of fuel under pressure to the tangential passages, means for returning a part of the fuel through the abutment plug and means for controlling the amount of fuel thus returned. 40
9. An apparatus for burning liquid fuel comprising a plurality of atomizers, a fuel return pipe from each atomizer, a fuel return pipe common to a group of burners, and means for separately controlling the flow of fuel through each of said return pipes. 45
10. An apparatus for burning liquid fuel comprising a plurality of atomizers, a fuel return pipe from each atomizer, a fuel return pipe common to a group of burners, a fuel return pipe common to a plurality of groups of burners, and means for separately controlling the flow of fuel through each of said return pipes. 50

In testimony whereof I affix my signature.
